WELDER'S MASK

Marshall N. Anderson, Chicago, Ill., assignor to
 Sellstrom Manufacturing Company, Chicago,
 Ill., a corporation of Illinois

Application June 12, 1939, Serial No. 278,717

12 Claims. (Cl. 2-8)

This invention relates to a welder's mask and more especially to the sight opening or window, with particular reference to the construction and arrangement of the lens support and the means for securing the lens support in the window opening of the mask, whereby the material thereof may expand and contract under any conditions, such as variations in temperature, without causing openings which might admit light or sparks to the interior of the mask, and also in which the lens holder will remain snugly in position in the light opening without the use of rivets or other means for rigidly securing the lens holder to the body of the mask.

Welders' masks are subject to extreme variations in temperature, and, as the masks and the lens support secured thereto have different coefficients of expansion, it has been very difficult to maintain a light proof joint therebetween. The common method of riveting the lens support to the mask, even when done with extreme care, is ineffective after the mask has been used a short time. The expansion and warpage of the material soon causes cracks and crevices to appear between the parts, which admit light and sometimes sparks or other foreign material, with disastrous results to the user. This has become a matter of extreme importance and such objections to prior structures have entirely been eliminated by the present invention in which the lens support is so constructed and mounted that all of the parts are free to expand and contract, or even warp considerably, without causing any direct opening therebetween, and, if any opening whatever is formed, it will be of such a tortuous nature that no light, sparks, or other foreign matter may pass therethrough.

It is an object to provide a lens support or lens carrier structure for supporting a multiple lens arrangement in which substantially all of the parts may be secured together and simultaneously secured in the sight opening of the mask by means of a minimum number of fastening members, which members will not interfere with the expansion and contraction of any of the elements in response to changes in temperatures.

A further object is the provision of a lens carrier of the character described having means for supporting a multiple lens arrangement in which a portion of the lens holder is arranged to carry a colored lens and in which this portion may be moved out of alignment with the lens opening and will resiliently be held in open position as long as desired.

A further object is the provision of a lens holder

which will be cheap to manufacture and which is of simple construction, easily assembled, and which may be manufactured of Bakelite, or similar suitable insulating material, or may be made of metal if desired.

Further objects will be apparent from the specification and the appended claims.

In the drawings:

Fig. 1 is a side elevation partially in vertical section of the usual welder's mask incorporating one embodiment of the invention.

Fig. 2 is a top view of the lens holder embodiment illustrated in Fig. 1 with the body portion of the mask shown in section.

Fig. 3 is a front elevation of the lens carrier or holder illustrated in Figs. 1 and 2 with part of the outer lens retaining frame and part of the outer lens broken away for purposes of illustration.

Fig. 4 is a vertical sectional view through the lens holder and is taken on a line substantially corresponding to line 4-4 of Fig. 3.

Fig. 5 is an end elevation of the lens holder with the outer hinged section raised out of alignment with the sight opening.

Fig. 6 is a vertical sectional view through the lens holder and is taken on a line substantially corresponding to line 6-6 of Fig. 3.

Fig. 7 is a longitudinal sectional view taken on a line corresponding to line 7-7 of Fig. 3.

Fig. 8 is a fragmentary front elevation of the outer lens holding frame.

Fig. 9 is a vertical sectional view taken on a line corresponding substantially to either of lines 35 9-9 of Fig. 8.

Fig. 10 is a perspective view of the inner lens holding clip.

Fig. 11 is a front elevation of another embodiment in which the hinged section is omitted.

Fig. 12 is a vertical sectional view taken on a line substantially corresponding to line 12-12 of Fig. 11.

Fig. 13 is a longitudinal sectional view through the embodiment shown in Fig. 11 and is taken on a line substantially corresponding to line 13-13 of Fig. 11.

Fig. 14 is a top view of the lens holding spring member.

Fig. 15 is a side view of the lens holder member shown in Fig. 14.

Fig. 16 is a front view of the sight opening in the body of the mask to receive the lens holder.

Referring to the drawings in detail, the embodiment illustrated comprises a mask of the usual type having a body portion 1 which is pref-

erably made of light, opaque, heat resisting material such as fiber, which may be pressed or molded or otherwise formed into suitable shape in accordance with requirements to provide a protection for the face and head. An adjustable head harness 2 is pivotally mounted to the sides of the mask at 3 in the usual well known manner and an adjustable chin rest 4 is secured to the inner front side of the mask, as shown. These general features form no material part of the present invention, and it is believed that further description thereof is unnecessary.

The present invention is particularly concerned with the construction of the sight opening and the lens holder supported therein. The lens holder embodiment illustrated in Figs. 1 to 10, inclusive, comprises a generally rectangular outer frame or base member 5 having a substantially rectangular opening therethrough. The side walls of this frame are comparatively thin and the inner edges are arcuate or otherwise formed, as shown at 6, to conform generally to the outer contour of the body portion 1 of the mask. The frame 5 is provided with an outwardly extending circumjacent flange 7 which corresponds to the inner curvature thereof and is adapted to engage the outer surface of the mask around the sight opening. The general shape of the sight opening in the body portion of the mask is illustrated in Fig. 16 and comprises a rectangular opening 8 having a laterally extending slot 9 at each end thereof to accommodate holder securing screws in a manner which will later be described.

The walls of the base member are preferably slightly angular, as shown at 10 (Fig. 7) and at 11 (Fig. 6). This provides a slightly tapered opening in the frame which is also provided at its outer edge with an inturned annular flange or stop member 12. In order to secure the base member 5 to the mask, a thin walled frame 13 is provided having an inner marginal flange 14 which is arcuate or otherwise shaped in accordance with the contour of the flange 7. The outer end of this inner frame is provided with an inturned flange 15 having an opening corresponding to the sight opening in the base 5 and in alignment therewith. In securing the lens holder to the mask, the frame member 14 is inserted through the rectangular sight opening 8 in the mask and telescoped into the member 5 until it strikes the stop member 12, as shown in Figs. 6 and 9. This limits the telescoping movement and prevents clamping the mask too snugly between the flanges 7 and 14. The frames are then secured snugly together by means of two oppositely disposed screws 16 extending through the flanges and through the slots 9 in the body of the mask, thereby retaining the holder in the sight opening while at the same time enabling free expansion of all of the parts and any opening therebetween will be of such a tortuous nature that no light or sparks may enter therebetween.

A loosely fitting lens 17 is positioned within the inner frame 13 and rests against the inturned flange 15. This lens may be of any suitable type but is preferably of clear glass and is retained in position by means of spring clips 18, one of which is secured adjacent each end of the lens holder by means of the corresponding screw 16. These lens clips are preferably of resilient sheet material and each is provided with a downwardly extending portion 19 which engages the end of the lens 17 and which tends to spring outwardly, thereby centering the lens and preventing lateral movement thereof and at the same time permit-

ting expansion and contraction of the lens and frame without danger of breakage. Each of the clips 18 is sheared from the bottom upwardly to provide a resilient tongue 20, the end of which engages the back face of the lens, as shown particularly in Fig. 7. It will be apparent from an inspection of Fig. 7 that the lens 17 may be inserted after the holder is mounted and the spring clips 18 secured in position. It is only necessary to insert the lens against the lateral pressure of the spring clips until the tongues 20 snap over the top of the lens as shown.

An important feature of the herein disclosed method of securing the lens holder to the mask is that the mask is positioned between two outwardly extending flanges on frames which are limited in their telescoping movement, as shown in Figs. 6 and 7, whereby the mask is not rigidly clamped and expansion and contraction thereof not restricted and yet in which such action will not cause openings to occur between the mask and the lens holder through which light or sparks may enter to the interior of the mask. As previously stated, it has been common practice to rivet a lens holder to the mask. However, variations in temperature or other conditions cause the mask to warp and wrinkle, particularly between the rivets, and thereby provide openings through which light may enter. It is, of course, understood that any light entering a mask from a welding operation may have serious consequences.

A hinged assembly 21, which is in itself a multiple lens holder, comprises a rectangular frame-like member 22 which is of substantially the same size as the base member 5 and, when closed, forms a continuation of the walls thereof. This frame member 22 is provided with an inwardly extending circumjacent flange 23 and is arranged in relation to the base member 5 to provide an overlapping joint 22a therewith of a type to prevent light entering therethrough. The frame 22 is provided with two upwardly extending curved hinge arms 24 which are pivoted to corresponding upwardly extending lug-like portions 25 which are slotted at 26 to receive the arms 24, these arms being pivoted at 27, whereby the lens assembly 21 may be raised out of alignment with the sight opening, as shown in Fig. 5. The hinge arms 24 are preferably shaped substantially as shown in Figs. 5 and 6 and are tapered to provide a substantially pointed end having a small groove 28 therein adapted to be engaged by a spring 29 having one end turned rearwardly and secured in the lug 26 as shown at 30. The opposite end of the spring 29 is turned outwardly at 31 to engage the end of the arm 24 when the assembly is raised in the position shown in Fig. 5. The pointed end of the arm 24 is related to the pivot and spring in such a manner that a substantial snap action of the lens assembly is provided when it is moved toward either its open or closed position, in either of which positions it will be retained by the spring until again moved by the user.

A rectangular lens holding frame or cover 32 having a corresponding sight opening therethrough is provided and is secured to the frame 22 by means of inwardly extending lugs 33 which overlap the frame 22, and screws 34 which are threaded into the frame. The cover frame 32 is also provided with downwardly extending lugs 35, as shown in Figs. 4 to 9. These lugs are preferably positioned adjacent the ends of the lens assembly, whereby they are conveniently posi-

tioned to enable the operator to raise the hinged assembly by using either of these lugs as a handle.

A colored lens or filter 36 and a cover lens 37, which latter may be of clear glass, are positioned in spaced relation in the lens assembly 21, as shown, and these lenses are held in spaced relation against the respective flanges of the lens holder by means of a spring wire frame or separator 38. One end wall 39 of the frame 22 is slightly shorter than the other walls to provide an elongated slot-like opening 40 for the insertion of the lens and resilient holder or separator 38. A gasket 41 of felt or fiber or other suitable material may be provided between the lens 36 and the flange 23.

The spring separator or lens retainer 38 is preferably in the general form of a rectangular loop, as shown in Fig. 14, with the ends of the wire laterally and upwardly extended and secured together to provide a short handle 42. The 20 spring member 38 is arcuately formed, as shown in Fig. 15, in order to resiliently retain the lenses in their normal separated position against the flanges, and the side bars are preferably formed somewhat as shown in Fig. 14 and the member 25 itself is preferably slightly narrower than the width of the holder frame 22 so that there is very little contact of the wire frame with the lens holder frame at any time. This is desirable in view of the intense heat which is sometimes applied to the lens holder and which is sometimes sufficient to fuse the lens retainer to the lens holder frame if sufficient contact therewith is maintained. With the present construction, the lens retainer has very little contact with the metal parts of the lens holder. The lens retainer 38 may be of any suitable material and of any appropriate cross sectional contour.

If desired, both lenses 36 and 37 may be placed 40 adjacent one of the inturned flanges with the retainer 38 between the lenses and the opposite flange as shown in Fig. 13.

Figs. 11, 12, and 13 illustrate a slightly different embodiment of the invention, in which the hinged lens holder assembly is omitted and a plurality of lenses are removably supported in the fixed lens holder. This embodiment comprises an outer frame 43 which is very similar in construction to the frame 5 previously described and is provided at its outer end with an inturned flange 44 which provides a stop for the inner frame. This frame 43 is provided at its opposite side with an outwardly extending flange 45 which may be arcuate in contour or any required shape to generally conform to the contour of the body of the mask around the sight opening.

An inner frame 46 is also provided which telescopes the frame 43 and is limited in position relative to the outer frame 43 by the stop 44. This inner frame is provided with a complementary laterally extending flange 47 for co-operation with the flange 45 to retain the holder in the sight opening. The inner and outer frame members are secured together by screws 48 extending through the slots 9 in the mask in the same manner as previously described. The inner member 46 is also provided with an inturned flange 49 which, when the device is assembled, is in spaced relation to the flange 44 in order to receive an inner lens 50 and an outer lens 51 in closely adjacent relation as in Fig. 13 or in spaced relation between the flanges as in Fig. 7. One of the end walls of the outer member or frame 43 is provided with an elongated slot 52,

52, through which the lenses 50 and 51 and one of the previously described spring separators or retainers 38 may be inserted in the assembled relation shown in Fig. 13, whereby both of the lenses may be retained against the flange 49 with the retainer exerting resilient pressure between the lenses and the outer flange 44. It will be obvious that the lenses 50 and 51 are removably and resiliently held in contactual relation, as shown, by means of the spring separator 38, or a thin gasket may be positioned between the lenses. Also a felt gasket 53 may be provided between the inner lens 50 and its associated flange if desired. It will be apparent also that, 15 in case either of the lenses 50 or 51 are broken or removed, the other lens will be held in place by the retainer 38. All of the lenses may be interchangeable to provide any desired arrangement of filters and cover lenses.

Modifications may be made without departing from the spirit of the invention, and it is therefore desired that the invention be limited only by the prior art and the scope of the appended claims.

Having thus described this invention, what is claimed and desired to be secured by Letters Patent is:

1. A lens holder comprising a main frame having a relatively wide surface adapted to substantially conform to the outer margin of a sight opening in a welder's mask, an inner frame adapted to extend outwardly through said sight opening and snugly telescope into said main frame and having a flange complementary to said surface to retain said mask therebetween, means to secure said frames together in said sight opening, an inturned flange in said inner frame, an inturned flange on said main frame, a pair of lenses supported by and between said inturned flanges, and a resilient retainer between said lenses for retaining them against their respective flanges.

2. A lens holder comprising a main frame having a relatively wide surface adapted to substantially conform to the outer margin of a sight opening in a welder's mask, an inner frame adapted to extend outwardly through said sight opening and snugly telescope into said main frame and having a flange complementary to said surface to retain said mask therebetween, means to secure said frames together in said sight opening, an inturned flange in said inner frame, an inturned flange on said main frame, a pair of lenses supported by and between said inturned flanges, and a resilient retainer between said lenses for retaining them against their respective flanges, and positionable between both lenses and an opposed flange.

3. A lens holder comprising a main frame having a relatively wide surface adapted to substantially conform to the outer margin of a sight opening in a welder's mask, an inner frame adapted to extend outwardly through said sight opening and snugly telescope into said main frame and having a flange complementary to said surface to retain said mask therebetween, means to secure said frames together in said sight opening, an inturned flange in said inner frame, an inturned flange on said main frame, a pair of lenses supported by and between said inturned flanges, and a resilient retainer between said lenses for retaining them against their respective flanges, said holder having a slot between said inturned flanges for the insertion and removal of said lenses and said separator.

4. A lens holder comprising a main frame having a relatively wide surface adapted to substantially conform to the outer margin of a sight opening in a welder's mask, an inner frame adapted to extend outwardly through said sight opening and snugly telescope into said main frame and having a flange complementary to said surface to retain said mask therebetween, means to secure said frames together in said sight opening, an inturned flange in said inner frame, an inturned flange on said main frame, a pair of lenses supported by and between said inturned flanges, and a resilient separator between said lenses for retaining them against their respective flanges, said separator comprising a resilient loop-like member adapted to engage the margins only of said lenses.

5. A lens holder comprising a main frame having a relatively wide surface adapted to substantially conform to the outer margin of a sight opening in a welder's mask, an inner frame adapted to extend outwardly through said sight opening and snugly telescope into said main frame and having a flange complementary to said surface to retain said mask therebetween, means to secure said frames together in said sight opening, an inturned flange in said inner frame, an inturned flange on said main frame, a pair of lenses supported by and between said inturned flanges, and a resilient retainer positionable between said lenses for retaining them against their respective flanges, or positionable between both lenses and an opposed flange, said holder having a slot between said inturned flanges for the insertion and removal of said lenses and said retainer, said retainer comprising a loop-like member adapted to engage the margins only of said lenses and having a handle extending through said slot.

6. A lens holder for insertion in the sight opening in a welder's mask comprising an inner frame adapted to be inserted in said sight opening and having a laterally extending circumjacent flange conforming generally to the inner contour of said mask, an outer frame adapted to telescope over said inner frame and having a complementary flange, means for securing said frames together, an inturned annular flange in said inner frame, a lens positioned against the inner side of said flange, and resilient lens retaining clips mounted on said holder and engaging the marginal edges of said lens and inner face thereof and arranged to resiliently retain said lens against lateral movement to enable easy insertion and removal of said lens by lateral pressure on said clips.

7. A lens holder for insertion in the sight opening in a welder's mask comprising an inner frame adapted to be inserted in said sight opening and having a laterally extending circumjacent flange conforming generally to the inner contour of said mask, an outer frame adapted to telescope over said inner frame and having a complementary flange, means for securing said frames together, said means comprising oppositely disposed screws, and spring clips secured by said screws with their free ends terminating adjacent said inturned flanges to engage the edges of said lens, said clips having resilient lens retaining tongues adapted to engage the inner face of said lens and operable to release said lens or enable insertion thereof by lateral pressure on at least one of said tongues.

8. In a lens holder of the character described having a pocket adapted to receive spaced lens holders therein, said holder having an open slot

communicating with said pocket for the insertion and removal of said lenses, a separator between said lenses, said separator comprising a resilient loop formed to contact opposed margins of both lenses with small loop-aligning portions of said loop closely adjacent the side walls of said pocket and the side spans between said portions bent inwardly out of engagement with said side walls, and a handle on said loop extending through said slot and freely accessible from outside said holder whereby said separator may be inserted and removed through said slot.

9. A lens holder for mounting in the sight opening of a welder's mask, comprising an inner frame adapted to be inserted in said sight opening and having a laterally extending circumjacent flange at its inner edge conforming generally to the inner contour of said mask and having an inturned flange at its outer edge, an outer frame adapted to telescope over said inner frame and having a complementary inner end flange and a complementary inturned outer edge flange, said inturned flanges being related for positive engagement to limit the spacing of said laterally extended flanges to prevent rigid clamping of said mask when said frames are secured together, means to secure said frames together independent of said mask, and means to support a lens in said inner frame against its inturned flange.

10. A lens holder for the sight opening of a welder's mask comprising an outer frame having its wall Z-shaped in cross section to form an outwardly extending flange at its inner end and an inwardly extending flange at its outer end, the outer corner of said frame having a rabbet groove therein to receive a cover frame, an inner frame with similar Z-shaped walls forming similar flanges and adapted to telescope into said outer frame through said sight opening with the inwardly extending flanges engaged to limit the spacing of said outwardly extending flanges to prevent rigid clamping of said mask, means for securing said frames together, and resilient means supported by said securing means to removably retain a lens in said inner frame against its inturned flange.

11. A lens holder for the sight opening of a welder's mask comprising an outer frame having its wall Z-shaped in cross section to form an outwardly extending flange at its inner end and an inwardly extending flange at its outer end, the outer corner of said frame having a rabbet groove therein to receive a cover frame, an inner frame with similar Z-shaped walls forming similar flanges and adapted to telescope into said outer frame through said sight opening with the inwardly extending flanges engaged to limit the spacing of said outwardly extending flanges to prevent rigid clamping of said mask, means for securing said frames together, and resilient means supported by said securing means to removably retain a lens in said inner frame against its inturned flange, said outer frame having a hinged cover frame thereon with its side walls resting in said rabbet groove and having an inner flange closely overlapping the inturned flange of said outer frame to provide a closed tortuous joint therebetween and one or more lenses mounted in said hinged frame.

12. A lens holder comprising a main frame having a relatively wide surface adapted to substantially conform to the outer margin of a sight opening in a welder's mask, an inner frame adapted to extend outwardly through said sight

opening and snugly telescope said main frame and having a flange complementary to said surface to engage the inner margin of said sight opening, means for rigidly clamping said frames together with said flanges in fixed spaced relation so that the marginal edges of said sight opening are in non-clamped relation therebetween, an inturned flange adjacent the outer end of said main frame and positioned for en-

gagement by said inner frame to maintain said flanges in predetermined spaced relation greater than the thickness of said mask, a lens mounted in said inner frame, and a lens mounted on said main frame in spaced relation to said first lens, resilient means for removably securing said first lens and additional resilient means for removably securing said second lens.

MARSHALL N. ANDERSON.
